CLAIM

The ornamental design for a compartmented oval container, as shown and described.

DESCRIPTION

FIG. 1 is a top plan view of a compartmented oval container, showing my new design;

FIG. 2 is an isometric view thereof;

FIG. 3 is a cross-sectional view taken on line I—I of FIG. 1 of the central rib portion thereof;

FIG. 4 is a right side view thereof;

FIG. 5 is a left side view thereof;

FIG. 6 is a front elevational view thereof;

FIG. 7 is a rear elevational view thereof; and,

FIG. 8 is a bottom view thereof.
